Primary Examiner — Sheryl Lane*Assistant Examiner* — Calvin E Vansant(74) *Attorney, Agent, or Firm* — Gary L. Eastman, Esq.;
Eastman & McCartney LLP(57) **CLAIM**

The ornamental design for a portable medical freezer cart, as shown and described.

DESCRIPTION

FIG. 1 is a top-front perspective view of a portable medical freezer cart;

FIG. 2 is a top-front-right perspective view of the portable medical freezer cart;

FIG. 3 is a bottom-back-right perspective view of the portable medical freezer cart;

FIG. 4 is a front elevational view of the portable medical freezer cart;

FIG. 5 is a back elevational view of the portable medical freezer cart;

FIG. 6 is a right side elevational view of the portable medical freezer cart;

FIG. 7 is a left side elevational view of the portable medical freezer cart;

FIG. 8 is a top plan view of the portable medical freezer cart; and,

FIG. 9 is a bottom plan view of the portable medical freezer cart.

The broken lines depict portions of the portable medical freezer cart and form no part of the claimed design.
